(57) **CLAIM**

(22) Filed: **Jun. 14, 2000**

The design for a ground-engaging tool for an excavation
bucket, as shown and described.

(51) LOC (7) Cl. **15-03**

DESCRIPTION

(52) U.S. Cl. **D15/29**

FIG. 1 is a perspective view of our new ground-engaging
tool for an excavation bucket;

(58) Field of Search D15/28, 29; 37/460,
37/450-453, 195; 299/527.5, 530, 109;
172/713

FIG. 2 is a bottom view thereof;

(56) **References Cited**

FIG. 3 is a top view thereof;
